THERMOCOUPLE SAFETY PILOT SWITCH

Leroy A. Matson, Forest Lake, Ill., assignor to
 Milwaukee Gas Specialty Company, Milwaukee,
 Wis., a corporation of Wisconsin

Application May 15, 1944, Serial No. 535,575

9 Claims. (Cl. 200—87)

1

This invention relates, in general, to an electric switch, and has particular relation to a thermocouple safety pilot switch.

The device which I shall describe hereinafter in connection with the drawing is particularly adapted for use with a thermocouple safety control device having an electromagnet connected in circuit with a thermoelectric generator and provided with an armature which is held attracted so long as the thermoelectric generator is heated, for example, by a pilot light for a main burner, and moves to retracted position when the pilot light is extinguished.

One of the main objects of the present invention is to provide an improved form of switch having switch operating means adapted to be pressed to move the armature to attracted position without closing the switch, and, thus, without establishing a supply of fuel for the main burner; the closing of my improved form of switch requiring not only release of the switch operating means, but, also, that the armature be held in attracted position by energization of the electromagnet by the heat, for example, of the pilot flame on the thermocouple.

Another object of the invention is to provide, as a part of the switch operating means, a plunger which has movement in opposite directions and forms an insulating enclosure for the switch contacts.

Another object of the invention is to provide, in conjunction with the plunger having movement in opposite directions, a pin having sliding movement in the plunger, and switch contacts which are moved into and out of engagement by relative movement between the plunger and the pin.

Another object of the invention is to provide a device of the class described in which the position of the operating button indicates whether the switch is open or closed.

Another object of the invention is to eliminate the necessity for resilient or spring contact carrying members; also the necessity for pivotal or swinging movement either in the armature carrying member or in the switch parts.

Another object of the invention is to provide a device of the class described in which the armature, the armature carrying parts, and the parts which carry and control the switch and move the armature to attracted position are all positioned coaxially and operated by rectilinear movement.

Another object of the invention is to provide a device of the character described which is adapted for installation with various types of burner and

2

furnace constructions, and may be mounted for use in any desired position.

Further objects and advantages of the invention will be apparent from the following detailed description, taken in connection with the accompanying drawing.

In the drawing:

Figure 1 is a schematic view showing one application of a switch embodying the present invention;

Figure 2 is an elevational view of the switch shown in Figure 1;

Figure 3 is a longitudinal sectional view taken on the line 3—3 of Figure 2;

Figure 4 is a longitudinal sectional view, similar to Figure 3, with the armature in attracted position and the switch closed; and

Figure 5 is a fragmentary longitudinal section taken on the line 5—5 of Figure 4.

In Figure 1 of the drawing, a gas or other fuel burner of any suitable or preferred type is illustrated at 10. The burner 10 may be the burner of a room or space heater, water heater, floor furnace, gas range, or any other burner. A gas or fuel supply pipe 11 leads to the burner 10 for the delivery of gas or other fuel thereto—for example, through a mixing chamber 12 to which air is admitted in the usual way, as well understood in the art.

An electroresponsive valve 13, such as a solenoid or motor valve, is interposed in the fuel supply pipe 11. The valve 13 is shown as comprising a valve body 14 and a hood 15 having any suitable power operated valve actuating means therein.

A step-down transformer 16 supplies power for the operation of the valve 13. This transformer comprises a line voltage primary 17 and a low voltage secondary 18. The primary 17 is connected to line wires 19 leading to any suitable source of current or power (not shown). The valve actuating means for the valve 13, the switch of the present invention, which is designated in its entirety at 20, and a thermostat, such as a room thermostat 21, are shown connected in series circuit relation in the secondary circuit 22.

For purposes of the present disclosure it may be assumed that the valve 13 is of a character to be actuated to open position by closing of the circuit 22, and to be held in open position to supply fuel to the burner 10 as long as the circuit 22 is closed. The valve 13 may have spring means or other suitable means for actuating the valve to closed position to shut off the supply of fuel to the burner 10 when the circuit 22 is opened or otherwise disabled.

A pilot burner 23 is placed in juxtaposition to the main burner 10 and provides a pilot light or flame 24 for lighting the main burner. A pipe 25, connected to the fuel supply pipe 11 anterior of the valve 13, or otherwise as desired, supplies fuel for the pilot burner 23.

The switch 20 has a generally U-shaped supporting bracket 26. The U-shaped magnet frame 27 is secured to a terminal bushing 28, for example, in the manner more fully disclosed in Clarence 10 Wantz U. S. Patent No. 2,318,823, issued May 11, 1943. The coil 29 of the electromagnet is wound around the legs of the magnet frame 27. The bushing 28, the shank of which extends through an opening in the adjacent end flange 30 of the bracket 26, is shown as externally threaded for threaded engagement with a nut 31 by means of which the bushing 28 is clamped to the flange 30. A sealing gasket 32 is preferably placed between the head or flange at the inner end of the bushing 20 and the flange 30.

A thermocouple, indicated at 35, is placed in position so that the hot junction 36 thereof will be heated by the pilot flame 24 as long as the pilot flame is burning. While the thermocouple 25 and leads therefor are shown as similar to the thermocouple and leads more fully disclosed in Oscar J. Leins Patent No. 2,126,564, issued August 9, 1938, it is to be understood that the thermocouple and its leads may be of any other suitable or preferred form within the scope of the present invention.

For the purpose of the present description, suffice it to state that the particular thermocouple selected for illustration comprises an outer tubular metallic thermocouple element and an inner metallic thermocouple element of different thermoelectric characteristics. The thermocouple elements are joined to form the hot junction 36. An outer tubular lead conductor 37 is connected to the outer thermocouple element, for example, through a sleeve 38. The inner lead conductor 39, enclosed by and insulated from the outer tubular lead conductor 37, is connected to the inner thermocouple element.

A quick detachable or removable connection is preferably provided between the electromagnet and the ends of the leads 37 and 39 opposite the ends which are connected to the thermocouple element. The inner lead 39 has a connector cone 40 which seats in the correspondingly recessed outer end of the terminal tip 41 and is clamped in contact therewith by a connector sleeve 42 which screws into the outer end of the bushing 28. The adjacent end of the outer tubular conductor 37 is connected in circuit with one side of the coil 29 through the connector sleeve 42 and the bushing 28, and the other side of the coil 29 is connected to the inner lead conductor through the terminal tip 41, the parts being suitably insulated.

The electromagnet is enclosed within a housing 45 preferably formed of insulating material, such as a plastic or synthetic resin. The base of the housing 45 is flanged at 46 and secured by screws 47 to the flange 30 of the bracket 26. The armature 48, also enclosed within the housing 45, is carried on the inner end of an armature stem 49 which extends out through the adjacent end of the housing for sliding movement, for example, in a metal insert 50.

The opening through which the stem 49 extends is sealed by suitable packing 51 held in place by a cup-shaped spring seat member 52. An abutment member 53 has its shank screwed into the

outer end of the stem 49, thus detachably securing the abutment member to this stem. A coil spring 54, interposed between the spring seat member 52 and a spring seating disc 55, moves the armature 48 to retracted position when it is released from the electromagnet.

Secured by screws 58 to the bracket or support 26 is a body member 60 preferably formed of insulating material, such as a plastic or synthetic resin. A plunger 61, also preferably formed of insulating material such as a plastic or synthetic resin, has rectilinear sliding movement in opposite directions in a bore 62 in the body member 60. A pin 63, preferably formed of insulating material, has sliding movement in the plunger 61. The pin 63, plunger 61, armature 48, and stem 49 are all coaxial.

The plunger 61 is recessed to receive and enclose the switch which comprises a pair of contacts 64, carried by the plunger 61, and a bridging contact disc 66 on the pin 63. The contacts 64 have terminals which extend out along the opposite longitudinal edges of the arcuate portion 68 of the body member 60. This arcuate portion 68 of the body member partially embraces the spring 54 and adjacent parts and, with the bracket 26, provides protection for these parts. The terminals for the contacts 64 are connected by flexible conductors 67 to metallic connector pieces 68 secured to the body member 60 by screws 69, which screws are also adapted to clamp the adjacent ends of the conductors 67 to the connector pieces 68. The conductors, which form a part of the circuit 22, are clamped to the respective connector pieces 68 by screws 70.

The open end of the plunger 61 is closed by an end member 71, which is also preferably formed of insulating material such as a plastic or synthetic resin. The plunger 61 and end member 71 move as a unit in opposite directions when the device is assembled as shown in the drawing, but upon removal of the body member 60 from the bracket 26 and removal of the plunger 61 from the body member the end member 71 may be removed from the plunger for access to the switch contacts. The end member 71 has an integral button 72 which extends out through an opening in the adjacent flange 30' of the bracket 26.

The pin 63 has, at its inner end, an enlarged head 74 which provides an abutment 75 which cooperates with the plunger 61, so that when the plunger is moved to the right from the position shown in Figure 3 the pin 63 will move as a unit with the plunger, and, by its cooperation with the abutment member 53, moves the armature 48 to attracted position. The headed end of the pin 63 is preferably rounded, as shown, to seat in a recess in the cooperating end of the abutment member 53.

A spring 80, coiled about the reduced end of the pin 63 and interposed between the bridging contact 66, which is loose on the pin, and the end member 71, acts, upon removing the finger from the button 72, when the movement of the armature 48 to attracted position is complete and the armature 48 is held in attracted position by the electromagnet, to move the plunger 61 to the left relative to the pin 63, from the position shown in Figure 3 to the position shown in Figure 4. This engages the contacts 64 with the bridging contact disc 66. A spring 81, which is weaker than the spring 80, is coiled about the end member 71 and interposed between the base of the end member and the flange 30'. The spring holds the plunger 61 and button in place and against dropping, for

example, from the position shown in Figure 4, when the device is mounted in vertical position, with the button directed downwardly.

For the purpose of indicating by the position of the button 72 whether the switch is open or closed, the button has a band or portion 72' thereof of red or other suitable color, or otherwise suitably marked. When the armature 48 is held in attracted position by the electromagnet, and the switch is closed, this band or colored or marked portion 72' of the button is concealed within the end of the body part 60 and the adjacent flange 30', as shown in Figure 4. When the armature is in retracted position and the switch is open, the band or colored or marked portion 72' is exposed beyond the end of the body part 60 and adjacent flange 30'. The presence or absence of the colored or marked portion 72' of the button beyond the end of the body part 60 and flange 30' thus enables the operator to determine at a glance whether the switch is open or closed.

To start the operation of the system shown in the drawing, the following sequence is followed:

The plunger 61 is pressed inwardly, for example, from the position shown in Figure 3, by engaging the button 72 with the hand or finger and pressing the same. The plunger 61, by its engagement with the abutment 75 on the pin 63, moves the pin 63 as a unit with the plunger and with the contacts 64 out of engagement with the contact 65. The pin 63, in its inward movement and by its engagement with the cooperating headed end 53 of the armature stem 49, moves the armature 48 by rectilinear movement from its retracted position, shown in Figure 3, to its attracted position, shown in Figure 4.

Upon ignition of the pilot burner 23, the pilot flame 24, by heating the hot junction 36 of the thermocouple 35, energizes the electromagnet sufficiently to hold the armature 48 in attracted position. When the button 72 is released with the armature 48 held in attracted position by the electromagnet, the spring 80 moves the plunger 61 to the left, as shown in the drawing, relative to the pin 63, and from engagement with the abutment 75 on the pin 63 to the position shown in Figure 4. This movement of the plunger 61 relative to the pin 63 moves the contacts 64 into engagement with the bridging contact 65 to close the circuit 22 at the switch 20. Assuming that the circuit is also closed at the thermostat 21, the valve 13 is opened by the completion of the circuit 22 for the supply of fuel to the main burner 10 which is then ignited by the pilot flame.

From the foregoing it will be apparent that the switch 20 closes the circuit 22 not by the inward movement of the button 72 or by the armature resetting operation, but only if and after the armature 48 is held in attracted position by the electromagnet and the button 72 is released. The closing of the circuit 22 and opening of the valve 13 for the supply of fuel to the main burner is thus prevented except when the pilot flame is ignited so that it will ignite the fuel which is delivered to the main burner.

If the heat of the pilot flame on the thermocouple has not generated sufficient E. M. F. to hold the armature in attracted position, the spring 54 will return the armature 48 to retracted position and the plunger 61 and pin 63 to the positions shown in Figure 3, the switch remaining open and the valve 13 remaining closed.

If, after the parts are set as shown in Figure 4

and the pilot burner is lighted to hold the parts in the positions shown in this figure, the pilot flame is extinguished, the armature 48 is released. The spring 54 then moves the armature 48 to retracted position, and the stem 49, by engagement with the pin 63, moves the pin 63 to the left, as the device is shown in Figure 4, relative to the plunger 61 until the abutment 75 engages the plunger. This separates the contact 65 from the contacts 64, thus opening the circuit 22 and closing the valve 13 to shut off the supply of fuel to the main burner. The continued movement of the armature stem 49 to the left as the device is shown in the drawing returns the plunger 61 and button 72 to the position shown in Figure 3. With the parts in this position the colored or marked band or portion 72' of the button 72 projects from the adjacent end of the body member 60 and flange 30', indicating that the switch is open. When the parts are in the position shown in Figure 4, the colored or otherwise marked portion 72' of the button 72 is concealed, thus indicating that the armature is held in attracted position and that the switch is closed.

25 The embodiment of the invention shown in the drawing is for illustrative purposes only, and it is to be expressly understood that the drawing and the accompanying specification are not to be construed as a definition of the limits or scope of the invention, reference being had to the appended claims for that purpose.

I claim:

1. In a device of the class described, in combination, a rectilinearly movable insulating plunger, a coaxial pin carried by and slidable axially in said plunger, an abutment on said pin for cooperation with said plunger whereby the pin is moved with the plunger in one direction, said plunger having movement in the opposite direction relative to said pin, and cooperating contact means on said plunger and said pin for movement into closed circuit cooperation by relative movement between said plunger and said pin.

45 2. A device according to claim 1 wherein the insulating plunger is of hollow form and the cooperating contact means is disposed within the hollow interior of said plunger.

50 3. In a control device of the class described, in combination, an electromagnet, an armature stem movable axially in opposite directions, an armature carried by said stem for movement to attracted position relative to said electromagnet by movement of said stem in one direction and to retracted position by movement of said stem in the opposite direction, an axially movable plunger coaxial with said armature stem and having an end wall, an actuating pin mounted for axial sliding movement in the end wall of said plunger at the axis thereof, said pin abutting endwise with 55 said armature stem on one side of the end wall of the plunger and having an abutment between its ends for cooperation with said plunger whereby axial movement of said plunger in one direction moves the actuating pin axially therewith and said armature to attracted position by the abutment of said actuating pin with said armature stem, said plunger having axial movement in the opposite direction relative to said actuating pin when the armature is held in attracted position and the plunger is released, and first and second contact means on the opposite side of the end wall of the plunger, said second contact means being maintained in open circuit relation separated from said first contact means upon 60 movement of said actuating pin with said plunger.

in moving said armature to attracted position and moved into closed circuit relation engaging said first contact means by movement of said plunger in the opposite direction relative to said actuating pin with said armature held in attracted position by said electromagnet.

4. A control device according to claim 3, wherein in the plunger is an insulating plunger of hollow form and said first and second contact means are disposed within the hollow interior of said plunger.

5. A control device according to claim 3, wherein in the plunger is an insulating plunger, with said first contact means carried by said insulating plunger and wherein said second contact means is carried by said actuating pin for movement to open circuit relation separated from said first contact means by movement of said actuating pin axially relative to said plunger in a direction opposite the direction for moving said armature to attracted position.

6. A control device according to claim 3, wherein in the plunger is an insulating plunger of hollow form and said first and second contact means are disposed within the hollow interior of said plunger with said first contact means carried by said plunger and said second contact means carried by said actuating pin for movement to open circuit relation separated from said first contact means by movement of said actuating pin axially relative to said plunger in a direction opposite the direction for moving said armature to attracted position.

7. A control device according to claim 3, wherein in the end of the actuating pin inwardly of said plunger has a rounded head and the adjacent end of the armature stem has an abutment member provided with a socket for cooperation with the rounded head of said actuating pin.

8. A control device according to claim 3, wherein in the plunger is an insulating plunger, with said first contact means carried by said insulating plunger and wherein said second contact means is carried by said actuating pin for movement to open circuit relation separated from said first contact means by movement of said actuating pin axially relative to said plunger in a direction opposite the direction for moving said armature to attracted position; and a spring interposed be-

tween a wall of said plunger and said second contact means and operable to move the plunger axially relative to said actuating pin and in a direction opposite the direction for moving said armature to attracted position when the armature is held in attracted position by the electromagnet and the plunger is released whereby to move said second contact means into engagement with said first contact means.

9. In a control device of the class described, in combination, an electromagnet, an armature movable rectilinearly to attracted position in which it is adapted to be held by said electromagnet and rectilinearly to retracted position, an actuator member movable rectilinearly in one direction to move said armature to attracted position and movable rectilinearly in the opposite direction, a coaxial insulating plunger member movable rectilinearly between said actuator member and said armature, a coaxial pin member slidable axially in said plunger member, a pair of contacts carried by one of said plunger and pin members, a cooperating contact carried by the other of said plunger and pin members, a rectilinearly movable armature stem coaxial with said pin and said armature and interposed therebetween, an adjacent abutment member having an opening through which said actuator member operates, and a coiled spring interposed between the plunger member and said abutment member and operating to hold the actuator member and plunger member against dropping from place when the device is positioned vertically with the actuator member directed upwardly.
